(57) CLAIM

The ornamental design for a foldable hair drier comb as shown and described.

DESCRIPTION

FIG. 1 is a front, right and top perspective view of a foldable hair drier comb, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view thereof, shown in a folded state;

FIG. 9 is a front view thereof, shown in a folded state;

FIG. 10 is a rear view thereof, shown in a folded state;

FIG. 11 is a left side view thereof, shown in a folded state;

FIG. 12 is a right side view thereof, shown in a folded state;

FIG. 13 is a top plan view thereof, shown in a folded state; and,

FIG. 14 is a bottom plan view thereof, shown in a folded state.

The broken lines shown in the drawings illustrate portions of the foldable hair drier comb that form no part of the claimed design.
